UNITED STATES PATENT OFFICE

159,861

DISPLAY STAND

Edwin Rothchild, Brooklyn, N. Y.

Application January 14, 1949, Serial No. 338

Term of patent 14 years

(Cl. D80—9)

To all whom it may concern:

Be it known that I, Edwin Rothchild, a citizen of the United States, residing at Brooklyn, in the county of Kings and State of New York, have invented a new, original, and ornamental Design for Display Stand, of which the following is a specification, reference being had to the accompanying drawings, forming part thereof.

In the drawings:

I claim:

The ornamental design for a display stand, as shown.

EDWIN ROTHCHILD.
